UNITED STATES PATENT OFFICE.

WILLIAM J. KEEP, OF DETROIT, MICHIGAN, ASSIGNEE TO MICHIGAN STOVE COMPANY,
OF DETROIT, MICHIGAN, A CORPORATION OF MICHIGAN.

GARBAGE-BURNER.

1,138,662.

Specification of Letters Patent. Patented May 11, 1915.

Application filed July 9, 1914. Serial No. 849,870.

To all whom it may concern:

Be it known that I, WILLIAM J. KEEP, a citizen of the United States of America, residing at Detroit, in the county of Wayne and State of Michigan, have invented certain new and useful Improvements in Garbage-Burners, of which the following is a specification, reference being had therein to the accompanying drawings.

10 This invention relates to garbage burners, and more particularly to stoves used as receptacles for garbage, which is consumed by the application of heat and fire.

15 The primary object of my invention is to provide a stove or reduction apparatus for the destruction of garbage, moist substances and waste products wherein the process of calcination is expeditiously and economically carried on, without disagreeable odors 20 incident to the burning of refuse matters.

Another object of my invention is to provide a garbage burner wherein positive and reliable means are employed, in a manner hereinafter set forth, to insure thorough 25 calcination of garbage, the process including the distribution of heated air until a state of transcellency is reached that insures incineration by a gas flame or similar agent. In carrying the process into effect, provision 30 is made for the expansion and contraction of such elements as are exposed to moisture and heat, also for a draft that affords a perfect combustion with a minimum expenditure of fuel.

35 A further object of this invention is to provide a garbage burner embodying a novel container or pot, a hot air distributing member, a tiltable grate and other instrumentalities that can be easily and quickly 40 assembled to provide a durable structure.

With the above and other objects in view, the invention resides in the novel construction, combination and arrangement of parts to be hereinafter specifically described and 45 then claimed, and reference will now be had to the drawings, wherein—

Figure 1 is a front elevation of the garbage burner, partly broken away and partly in section; Fig. 2 is a vertical sectional view 50 of the garbage burner; Fig. 3 is a horizontal sectional view taken on the line III—III of Fig. 2; Fig. 4 is a similar view taken on the line IV—IV of Fig. 2; and Fig. 5 is a perspective view of a detached grate adapt-

ed to form the bottom of a foraminous fire pot.

In describing my invention by aid of the views above referred to, I desire to point out that I intend the same as merely illustrative of an example whereby my invention 60 may be applied in practice, and I do not care to limit the invention to the exact arrangement and construction of parts shown. The following description is therefore to be broadly construed as including substitute 65 arrangements and constructions which are the obvious equivalent of those to be herein-after referred to.

In the drawings, the reference numeral 1 denotes a substantially rectangular base 70 supported by legs 2 and on the base are ribs and lugs 3 for correctly positioning the stove proper.

The stove proper comprises an outer casing having a front wall 4 provided with longitudinal side channels 5 to receive the connected edges of inner and outer spaced shells 6 and 7 respectively, the inner shell being of less length than the outer shell and having the ends thereof riveted or otherwise secured as at 8 to the outer shell. The shells form a vertical flue or draft space 9 to which air is admitted by a series of openings or perforations 10 in the outer shell adjacent the lower end thereof. The inner shell 6 has the upper ends thereof provided with a series of openings or perforations 11 establishing communication between the draft space 9 and the upper part of the stove casing. The upper edges of the outer casing supports a top or cover 12 having an exhaust chimney or stack 13.

The base 1 supports a fire box 14, a garbage container or pot 15 and a dome 16, said elements being integrally formed, as best 95 shown in Fig. 2. The dome 16 has the top thereof provided with a flanged opening 17 over which is fitted a flue 18 that extends into the chimney or stack 13. The front side of the dome 16 has a chute or opening 19 communicating with a walled opening 20 of the front wall 4 and said opening is normally closed by a door 21 or suitable closure.

The garbage container or pot 15 is cylindrical and of greater diameter than the base of the dome 16. At the junction of the pot 15 and the dome 16 there is a lateral 105

flange 22 that engages the front wall 4, but is spaced from the inner shell 6 of the stove casing in order to support a depending apron 23 which co-operates with the walls 5 of the pot 15 in providing an air heating chamber 24 that has the lower end thereof open and in communication with the space between the fire box 14 and the stove casing in order to receive cold air through a 10 series of openings 25 in the base 1. The pot 15, at the juncture of the fire box 14 therewith, has another lateral flange 26 engaging the front wall 4 and closing the lower end of the air heating chamber 24 at 15 the front side of the stove. The air heating chamber at this side of the stove is in communication with a lateral inwardly projecting hollow arm 27 supporting a vertically disposed concentric hot air distributing 20 member or drying chamber 28 within the pot, said member having perforations 29 that form a foraminous body capable of disseminating hot air in and through garbage placed in the pot. The air distributing 25 member 28 extends into the dome 16 and has the upper end thereof closed and braced by a fork 30 carried by an angularly disposed support 31 suitably secured to the inner wall of the dome 16. The air distributing 30 member 28 is fluted throughout its length and in cross-sectional area conforms to a Maltese or eight-pointed cross. The perforations or openings of the member are disposed whereby heated air will be directed 35 and distributed in various directions in the pot 15, thereby effecting a rapid drying and ustulation of the contents of the pot, as will hereinafter appear.

The walls of the pot 15, contiguous to the 40 upper end thereof, are provided with inwardly projecting hooks or hangers 32 to receive straps or brackets 33 of a cylindrical grate 34 composed of vertically disposed bars having the upper and lower ends thereof 45 connected by rings 35. The lower end of the cylindrical grate is provided with outwardly extending spacing lugs 36 and these lugs co-operate with the straps or brackets 32 in correctly positioning the cylindrical 50 grate relative to the walls of the pot 15. The cylindrical grate 34 has the front sides thereof provided with a bridge 37, as best shown in Fig. 1, said bridge providing clearance for the lateral arm 27 of the air distributing member 28.

At the junction of the fire box and the garbage pot is a tiltable or dumpable horizontally disposed grate having alining trunnions 39 and 40 that are offset relative 60 to the diameter of the grate. The rear trunnion 39 is supported by a socket member 41, carried by the wall of the fire box 14, and the forward trunnion 40 is journaled in the front wall 4 of the stove casing. The outer end of the forward trun-

nion 40 is shaped to accommodate a crank or lever (not shown) whereby the grate can be tilted and matter thereon dumped or deposited in a pan or receptacle 42 placed in the lower part of the fire box.

To support the grate 38 in a horizontal position whereby it will form the bottom of the garbage pot 15, a side wall of the fire pot has a slidible keeper 43 that protrudes through an angularly disposed portion 44 of the front wall 4. The inner end of the slidible keeper 43 has a lateral projection 45 which extends under the peripheral edge of the grate 38 and co-operates with the trunnions thereof in maintaining the grate in a horizontal position. By simply withdrawing the extension 45 the grate 38 is free to tilt by gravity or when supporting ashes it may be tilted by placing a crank or lever in engagement with the forward trunnion 40. The grate, as best shown in Fig. 5, has the bars 46 thereof integral with the front side of the grate ring and the rear ends of said bars free of the rear side of the grate ring. This is accomplished by placing sheets of mica in the mold employed in producing the grate, and by having the rear ends of the bars 46 separate from the ring, expansion and contraction of said bars can take place without any danger of the ring being fractured. Of course this feature of the grate can be eliminated without impairing the use of the garbage burner.

The angularly disposed portion 44 of the front wall 4 is provided with openings to 100 accommodate a series of gas burners 47 that extend into the fire box and are supported by a bracket 48 within the fire box and a gas supply pipe 49 mounted in brackets or holders 50 provided therefor at the front 105 side of the stove. The burners have air mixers, controlling valves and other necessary appurtenances, and above the burners the angularly disposed portion 44 has an opening 51 that permits of easy access being had to the inner ends of the burners whereby gas can be ignited. The opening 51 is normally closed by a door 52. Besides this door the front wall 4 has another door 53 that permits of the ash pan or receptacle 110 42 being removed.

In operation, I will assume that the garbage container or pot 15 contains garbage which is held by the vertical cylindrical grate 34 and the horizontally disposed 120 grate 38, the garbage or refuse matter surrounding the central vertically disposed air distributing member. When the burners 47 are placed in operation the flames pass between the bars of the grate 38 and upwardly 125 between the bars of the grate 34 and the walls of the pot 15. Exposed portions of the garbage are dried and burnt and the inner wall of the air heating chamber 24 is heated sufficiently to heat the air that passes 130

upwardly between the wall of the pot 15 and the apron 23. The heated air is conveyed by the hollow arm 27 to the distributing member 28 and those portions of garbage surrounding said member are dried and made friable to be reduced by incineration and eventually deposited in the ash pan or receptacle. If the flames do not enter between the grate bars with sufficient rapidity to consume dried portions of garbage, the flames will pile up and enter the passages between the bars of the vertical grate 34, and as the garbage is consumed the hot air issuing from the distributing member 28, ignites with the inflammable gases and aids combustion. It is only a short period of time, however, until the state of translucency is reached which insures incineration of the garbage by the gas flame, and during this time combustion is sustained by the various air inlets of the stove structure.

With the draft between the inner and outer shells 6 and 7 of the stove casing there is always a sufficient amount of air entering the chimney or stack to carry off heat and while some of the air is supplied through the medium of the openings 10 and 11, another quantity of air is supplied by the openings 25. These last mentioned openings are employed purposely for supplying air to the apron and the central distributing member 28, but quantities of air will pass upwardly outside of the apron and enter the chimney 13.

From the foregoing it will be observed that my invention possesses the following characteristics and inherent advantages:— First, a foraminous fire pot having a central air distributing member that permits of the process of calcination being carried into effect for rapidly consuming the garbage placed in the pot. Second, a foraminous fire pot for garbage that has a central air distributing member and an encircling air heating chamber for supplying air to said member, thus permitting of waste matters being consumed without retarding the heating propensities of the apparatus. Third, a fire and air feed incinerating receptacle that has a tiltable bottom permitting of residue being easily removed from the receptacle, the tiltable bottom being constructed to withstand an intense heat and such expansion and contraction to which it may be susceptible during the operation of the garbage burner. Fourth, a reduction apparatus embodying a receptacle having a drying chamber therein and means for supplying a drying agent to said chamber, thereby suggesting a structure other than the outline of a stove.

What I claim as my invention is:—

1. In a gas burning garbage incinerator, a foraminous pot adapted to contain garbage, an imperforate wall surrounding said pot

for maintaining a flame against the garbage exposed by the foramina of the pot whereby the garbage is dried and eventually burned, an apron coöperating with said imperforate wall in providing an air heating chamber, and a perforated drying chamber throughout the length of said pot receiving air from said chamber heated by the flame acting on the imperforate wall for subjecting the garbage to a drying to increase the porosity of the same, thereby preparing it for admission of the flame for incinerating purposes.

2. A garbage burner comprising a vertical grate, a tiltable grate at the bottom thereof coöperating with said vertical grate in providing a foraminous pot adapted to contain garbage, burners below said tiltable grate, an air heating chamber surrounding said vertical grate with the inner wall thereof deflecting the flame of said burners against garbage in said grate, and heating air admitted to said chamber, and means for conducting heated air from the lower part of said chamber to a point centrally of said vertical grate.

3. A garbage burner comprising a vertical grate, a tiltable grate at the bottom thereof coöperating with said vertical grate providing a foraminous pot adapted to contain garbage, burners below said tiltable grate, an air chamber surrounding said vertical grate with the inner wall thereof deflecting the flame of said burners against garbage in said grate and heating air admitted to said chamber, and a perforated drying chamber longitudinally of said vertical grate receiving air from said air chamber and discharging the air into the garbage in the direction toward the flame attacking the garbage.

4. A garbage burner comprising a vertical grate, a grate at the bottom thereof coöperating with said vertical grate in providing a foraminous pot adapted to contain garbage, burners below said bottom grate, an air chamber surrounding said vertical grate with the inner wall thereof deflecting the flame of said burners against garbage in said grate and heating air admitted to said chamber, and means throughout the length of said vertical grate and in communication with the lower part of said air heating chamber for disseminating air in the garbage in the direction of the flame attacking the garbage.

5. A garbage burner comprising a vertical grate, a tiltable grate at the bottom thereof coöperating with said vertical grate in providing a foraminous pot adapted to contain garbage, burners below said tiltable grate, an air heating chamber surrounding said vertical grate with the inner wall thereof deflecting the flame of said burners against garbage in said grate and heating air admitted to said chamber, said chamber having the lower end thereof closed at the front thereof, and means communicating with the

lower closed end of said chamber for conducting heated air centrally of said vertical grate and into garbage held thereby.

6. A garbage burner comprising a vertical grate, a tiltable grate at the bottom thereof cooperating with said vertical grate in providing a foraminous pot adapted to contain garbage, burners below said tiltable grate, an air heating chamber surrounding said vertical grate, the inner wall thereof deflecting the flame of said burners against garbage in said grate and heating air admitted to said chamber, said chamber having the lower end

thereof closed at the front of the chamber, and a perforated drying chamber longitudinally of said vertical grate communicating with the lower closed end of said air heating chamber for disseminating air in the garbage in the direction of the flame attacking the garbage.

In testimony whereof I affix my signature in presence of two witnesses.

WILLIAM J. KEEF.
